UNITED STATES PATENT OFFICE

ERNST FRÖLICH, OF ESSEN, GERMANY, ASSIGNOR TO THE HANNAUER CAR RETARDER COMPANY, OF GIBSON, INDIANA, A CORPORATION OF ILLINOIS

CAR RETARDER FOR RAILWAY SWITCHING YARDS

Application filed February 21, 1927. Serial No. 169,883.

My invention relates to improvements in railway car retarding apparatus adapted to be positioned at predetermined points along the track rails of a railway switching yard.

5 The principal object of the invention is to provide an improved apparatus of the above character, the wheel gripping members of which are adapted to be moved into gripping engagement with the side faces of the car 10 wheels at a point near the top of the running rail, and to so construct and arrange the cooperating parts of the apparatus that the gripping members will be moved automatically by the weight of the car into frictional engagement with the wheels of the car so as to retard its movement and which will automatically relieve said grip on the wheels should the wheels raise relative to the track rail.

20 Another object is to provide apparatus of this character having wheel-gripping elements movable into engagement with the opposite side faces of car wheels, which gripping elements are supported in their operating position by mechanism adapted to absorb the shocks and thrusts to which the gripping members are subjected when in service and which means is resiliently movable to compensate for variations in size or position of the car wheels.

Another object is to provide in an apparatus of the above character wheel gripping members which are movable horizontally into gripping engagement with the opposite side faces of the car wheels and which are maintained in their operative gripping engagement with the side faces of the car wheels by mechanism controlled at a remote point in the railway switching yard.

40 Another object is to provide in an apparatus of the above character wheel-gripping members which so cooperate with each other as to exert a yielding shackle grip on opposite side faces of the railway car wheels and which are moved into engagement with the side face of the wheel by the movement of the wheel passing over the apparatus.

Another object is to provide an apparatus of this character in which the wheel-gripping members may be moved to such position rela-

tive to the track rail as to provide sufficient clearance for the relatively wide locomotive wheels or other parts of a locomotive or railway car likely to interfere with the proper operation of the apparatus or likely to be injured by engagement with the apparatus.

55 A further and more specific object of the invention is to provide reliable operating mechanism which may be actuated from a remote point so as to move the wheel gripping members into normal operative position and which may be further actuated to increase the gripping pressure of said members on the car wheels or to relieve said gripping pressure as may be desired.

60 The invention consists in the new and improved arrangements, constructions and combinations of parts and devices hereinafter described and claimed for carrying out the above stated objects and such other objects as will appear from the detailed description of the embodiment of the invention shown in the accompanying drawings.

65 In the drawings, wherein like reference characters are used to designate like parts—

70 Fig. 1 is a fragmentary plan view of a portion of a retarding apparatus constructed in accordance with my invention.

75 Fig. 2 is a cross-section taken through the apparatus on line 2—2 of Fig. 1 and showing the car wheel gripping members in operative engagement with the side faces of car wheels, and

80 Fig. 3 is a fragmentary sectional view taken on line 3—3 of Fig. 2.

85 The embodiment of the invention herein illustrated consists of a plurality of wheel-gripping members designated generally by the reference characters 10 and 11 and arranged, respectively, along the outer and inner sides of each of the track-rails 13 and 14, and a plurality of pressure exerting members 15 for positioning and supporting the wheel gripping members in their normal operative position adjacent the said track rails. The 90 number of wheel gripping members employed in any particular apparatus will depend upon the length of the apparatus. The 95 wheel gripping members for frictionally engaging the outside faces of the car wheels, 100

consist of a plurality of short bars 16, overlapped at their ends, and supported on pivoted supporting members 17 so that they are normally parallel to the outside faces of the rails 13 and 14. Relatively long brake shoe members 18 are disposed adjacent each of the track rails and are secured to the short bars 16 so that movement of the latter toward the adjacent track rail will bring the shoe member into frictional engagement with the outside faces of the car wheels at opposite sides of the track. The supporting members 17 may be of any suitable shape. In the drawings I have shown these members as inverted U-shaped members pivoted at their lower ends on shafts 19 which extend through the transverse channel members 20—20. The members 17 are preferably of such length that the transverse movement of the members from their normal position to their wheel-gripping position is substantially in a horizontal plane.

The wheel gripping members 11 are preferably the same in construction as the members 10 and are therefore given the same reference numerals, with the addition of exponent α . The members 11 are preferably parallel with the inside faces of the track-rails 13 and 14, so that a lateral movement toward the track rails will bring the shoe members 18 α into frictional engagement with the inside faces of the car wheels at opposite sides of the track.

Spaced connecting links 21, 21 are connected at 22 to the pivoted members 17. The other ends of these link members are slidably supported on a beam 23 by means of shafts 24—24. Each of the shafts 24—24 support a bell crank lever 25 having a long arm 26 and a short arm 27. The short arm 27 of each lever is bifurcated and carries a roller 28, which bears against the inner edge of the short bars 16 α . The extremity of the long arm 26 supports a bar 29 adapted to be depressed by the flanges of the car wheels. The bars 29—29 may be made of any desired length. For example, they may be made so as to extend the full length of one complete apparatus or they may be made of such length as to be supported by two or more of the levers 25. A spring 30 is carried by the spring plate 31 supported on the links 21—21 so as to bear upwardly on the long arm of the levers 25 so as to support the bar 29 in a position to be engaged by the flanges of the car wheels passing over the apparatus.

The beam 23 is pivotally supported at 31 by the pressure mechanism 15. The pressure mechanism is disposed near the center of the track so that pressure at one end of the beam will be equalized by the pressure at the opposite end of the beam. The beam may be raised and lowered by the pressure mechanism so as to increase or release the pressure of the wheel gripping members on a car

wheel. Various pressure mechanisms may be employed for this purpose. I prefer, however, to employ the hydraulically operated piston 32 and cylinder 33. Preferably all of the cylinders 33 of one operating unit are connected by means of branch pipes 34 to a fluid supply pipe 35. The upward movement of the piston 32 is preferably limited by a stop member 36. The stop member preferably engages the clevis end of the piston so as not to interfere with the balancing action of the beam 23.

In operation, the pressure in the several cylinders 33 is normally such as to support the beam 23 and wheel gripping members 10 and 11 in their normal operative positions. In this position of the mechanism, the bars 29—29 are in position adjacent each of the rails to be engaged by the flange of the car wheels. When the bars 29—29 are engaged by the flanges of the car wheels, the bars are depressed and thereby rock the levers 25 so as to force the rollers 28 against the short bars 16 α and thereby force the shoe members 18 α —18 α against the inner faces of the car wheels at opposite sides of the track. As soon as the gripping members are in engagement with the inner faces of the car wheels, the further downward movement of the levers 25 slides the shafts 24—24 longitudinally of the equalizer beam 23 and simultaneously move the outer gripping members 10—10 into engagement with the outer faces of the car wheels. This gripping action effects, as it will be seen, a yielding toggle grip on opposite faces of each of the car wheels. In the event that the wheels raise with relation to the track rails, the upward movement will permit the levers 25 to move upwardly and thereby relieve the pressure of the wheel-gripping members on opposite sides of the car wheels. The fluid pressure exerted against piston 32 provides a resilient cushion for absorbing the shocks and pressures produced by the engagement of the wheel flanges with the bars 29—29. The initial engagement of the wheel gripping members with the wheels of a car will depress the piston to the position indicated in Fig. 2. The resiliency of the fluid pressure forces the equalizer bar upwardly and thereby tends to increase the pressure of the wheel engaging members on opposite faces of the car wheel.

By releasing the pressure in the cylinder 33, the equalizer will be lowered, thereby permitting the wheel gripping members to be moved transversely and downwardly with respect to their normal operative position, and thereby provide sufficient clearance to permit the relatively wide drive wheels of locomotives to pass over the apparatus without being engaged by the wheel gripping members. This release of the pressure in the cylinders 33 will also permit the train to be moved, as

a whole, without any frictional resistance on the part of the retarding apparatus.

While I have illustrated an apparatus which I now regard as my preferred embodiment, it will be understood, however, that the apparatus may be modified in various ways without material departure from the construction and equivalents of devices shown. It will therefore be understood that

10 I contemplate all such modifications in structure as come within the scope of the appended claims.

I claim:

1. In apparatus for retarding movement 15 of railway cars, a wheel engaging member movable substantially horizontally into frictional engagement with a side face of a wheel, a lever positioned to be rocked downwardly by the wheel and formed to engage said wheel 20 engaging member to force it into engagement with the wheel, and means for supporting the wheel engaging member in its normal operative position relative to the track rail and for increasing the pressure of said engaging 25 member against said wheel.

2. In apparatus for retarding movement of 30 railway cars, wheel engaging members disposed adjacent the track rails on opposite sides of said rails and movable into frictional engagement with the side faces of railway 35 car wheels, an equalizer beam extending transversely of the track, a lever supported by each end of the equalizer in a position to be depressed by the wheels of a car passing over the said apparatus, said levers being formed to engage certain of said wheel engaging members to force each of said members into engagement with the wheels.

3. In apparatus for retarding the movement 40 of railway cars, wheel engaging members disposed adjacent the track rails at opposite sides of the track and movable into frictional engagement with the side faces of railway car wheels, an equalizer beam extending 45 transversely of the track, a lever supported by each end of the equalizer in a position to be depressed by the wheels of the car passing over the apparatus, said levers being formed to engage certain of said wheel engaging members to force each of said members into engagement with the wheels, and 50 resilient pressure means for supporting said equalizer in its operative position.

4. In apparatus for retarding the movement 55 of railway cars, wheel engaging members disposed on opposite sides of each of the track rails, and movable substantially horizontally into gripping engagement with the inner and outer side faces of the wheels of the 60 car passing over the apparatus, an equalizer beam extending transversely of the track, links attached at their outer ends to the wheel engaging members for engaging the outside faces of the wheels and slidably supported at 65 their inner ends on the opposite ends of said

equalizer beam, levers carried by the inner ends of said links in position to be depressed by said car wheels; said levers being formed to engage the wheel engaging members for bearing against the inner faces of the car 70 wheels whereby the depressing of said levers forces the wheel gripping members into frictional engagement with the opposite side faces of the car wheels.

5. In apparatus for retarding the movement of railway cars, wheel engaging members disposed on opposite sides of each of the track rails and movable substantially horizontally into gripping engagement with the inner and outer side faces of the wheels of a 80 car passing over the apparatus, an equalizer beam extending transversely of the track, links attached at their outer ends to the wheel 85 engaging members for engaging the outer faces of the car wheels and slidably supported at their inner ends on the opposite ends of said equalizer beam, levers carried by the inner ends of said links in position to be depressed by said car wheel; the said levers being formed to engage the wheel 90 engaging member for bearing against the inner faces of the car wheels, whereby the depressing of said levers forces the said gripping members into frictional engagement with the opposite side faces of the car wheels, and means for exerting resilient pressure upwardly on said equalizer beam.

6. In apparatus for retarding the movement of railway cars, wheel engaging members supported on pivoted supporting arms 100 at opposite sides of each of the track rails and movable substantially horizontally into gripping engagement with the inner and outer side faces of the wheels of a car passing over the apparatus, an equalizer beam 105 extending transversely of the track, links attached at their outer ends to the wheel engaging members for engaging the outside faces of the wheel, and slidably supported at their inner ends on the opposite end of said equalizer beam, levers carried by the inner ends of said links in position to be depressed by said car wheel; the said levers being formed to engage the wheel-engaging 110 member for bearing against the inner faces of the car wheels, whereby the depressing of said lever forces the wheel gripping members into frictional engagement with the opposite side faces of the car wheels.

7. In apparatus for retarding the movement of railway cars, wheel engaging members comprising a plurality of short bars arranged along opposite sides of each of the track rails and provided with brake shoes and adapted to be moved substantially horizontally into gripping engagement with the inner and outer side faces of car wheels passing over the apparatus, an equalizer beam extending transversely of the track, links attached at their outer ends to the 125

wheel engaging members engaging the outside faces of the wheel and slidably supported at their inner ends on the opposite ends of said equalizer beam, levers carried by the inner ends of said links in position to be depressed by said car wheels; the said levers being formed to engage the wheel-engaging members for bearing against the inner faces of the car wheels, whereby the depressing of said levers forces the wheel gripping members into frictional engagement with the opposite side faces of the car wheels.

8. In apparatus for retarding the movement of railway cars, wheel engaging members comprising a plurality of short bars overlapped at their ends and supported on the upper end of pivoted arms so as to be moved substantially horizontally into gripping engagement with the inner and outer faces of car wheels passing over the apparatus, an equalizer beam extending transversely of the track, links attached at their outer ends to wheel engaging members for engaging the outside faces of the wheels and slidably supported at their inner ends on the opposite ends of said equalizer beam, levers carried by the inner end of said links and formed with a long arm and a short arm; the said long arm of said lever being attached to a bar extending longitudinally of the apparatus and adapted to be depressed by the flange of the car wheel passing over the apparatus and the said short arm being formed with a roller adapted to engage the inner edge of the wheel-engaging member for gripping the inner faces of the car wheel, whereby downward movement of the long arm of said lever forces the wheel gripping members into engagement with opposite faces of the car wheels.

9. In a vehicle retarder for railway rolling stock, the combination of vehicle wheel engaging shoes, said shoes being disposed adjacent fixed railroad rails, means for setting said shoes in braking position, said means including a bell crank operated by vehicle wheel contact with one leg thereof, the other leg thereof contacting a portion of said shoe to move the shoe to said braking position.

50 10. In a vehicle retarder for railway rolling stock, the combination of vehicle wheel engaging shoes, said shoes being disposed adjacent fixed railroad rails, means for setting said shoes in braking position, said means including a bell crank operated by vehicle wheel contact with one leg thereof, the other leg thereof contacting a portion of said shoe to move the shoe to said braking position, and resilient means for returning said bell crank to inoperative position.

11. In a vehicle retarder for railway rolling stock, the combination of vehicle wheel engaging shoes, said shoes being disposed adjacent fixed railroad rails, means for setting said shoes in braking position, said means in-

cluding a bell crank operated by vehicle wheel contact with one leg thereof, the other leg thereof contacting a portion of said shoe to move the shoe to said braking position, and means cooperating with said bell crank whereby braking pressures and operation of said shoes may be selectively varied.

12. In a car retarder, the combination of brake shoes disposed on either side of a rail and adapted to be moved into braking engagement with a car wheel, a wheel actuated member pivotally mounted on a floating member pivoted to one of said shoes, said wheel actuated member being adapted to be moved into engagement with the other of said shoes to move said other shoe to braking position and to thereby cause said floating member to move said first named shoe to braking position.

13. In a car retarder, the combination of brake shoes disposed on either side of a rail and adapted to be moved into braking engagement with a car wheel, a wheel actuated member pivotally mounted on a floating member pivoted to one of said shoes, said wheel actuated member being adapted to be moved into engagement with the other of said shoes to move said other shoe to braking position and to thereby cause said floating member to move said first named shoe to braking position, and means co-operating with said wheel actuated member whereby braking pressures and operation of said shoes may be selectively varied.

14. In a car retarding device, the combination of brake shoes disposed on each side of track rails, said brake shoes being mounted on articulated members pivotally mounted adjacent said rails, floating members pivotally connected to brake shoes disposed on one side of said rails and each extending to a point adjacent brake shoes on the opposite sides of said rails, bell cranks pivotally carried by said floating members and operatively engaging the articulated members of said last named brake shoes, said bell cranks each having an arm adapted to be engaged by the wheel of a track vehicle to thereby move said last named brake shoes into wheel engaging position to cause actuation of said floating member to move said other brake shoes into wheel engaging braking position.

15. In a car retarding device, the combination of brake shoes disposed on each side of track rails, said brake shoes being mounted on articulated members pivotally mounted adjacent said rails, floating members pivotally connected to brake shoes disposed on one side of said rails and each extending to a point adjacent brake shoes on the opposite sides of said rails, bell cranks pivotally carried by said floating members and operatively engaging the articulated members of said last named brake shoes, said bell cranks each having an arm adapted to be engaged by the wheel of a track vehicle to thereby move said last named brake shoes into wheel engaging

position to cause actuation of said floating member to move said other brake shoes into wheel engaging braking position, and resilient means co-operating with said bell cranks for returning said brake shoes to inoperative position.

16. In a car retarding device, the combination of brake shoes disposed on each side of track rails, said brake shoes being mounted on articulated members pivotally mounted adjacent said rails, floating members pivotally connected to brake shoes disposed on one side of said rails and each extending to a point adjacent brake shoes on the opposite sides of said rails, bell cranks pivotally carried by said floating members and operatively engaging the articulated members of said last named brake shoes, said bell cranks each having an arm adapted to be engaged by the wheel of a track vehicle to thereby move said last named brake shoes into wheel engaging position to cause actuation of said floating member to move said other brake shoes into wheel engaging braking position, resilient means cooperating with said bell cranks for returning said brake shoes to inoperative position, and means cooperating with said bell cranks whereby braking pressures and operation of said shoes may be selectively varied.

17. In a car retarding device, the combination of brake shoes disposed on each side of track rails, said brake shoes being mounted on articulated members pivotally mounted adjacent said rails, floating members pivotally connected to brake shoes disposed on one side of said rails and each extending to a point adjacent brake shoes on the opposite sides of said rails, bell cranks pivotally carried by said floating members and operatively engaging the articulated members of said last named brake shoes, said bell cranks each having an arm adapted to be engaged by the wheel of a track vehicle to thereby move said last named brake shoes into wheel engaging position to cause actuation of said floating member to move said other brake shoes into wheel engaging braking position, resilient means cooperating with said bell cranks for returning said brake shoes to inoperative position, and means cooperating with said floating members for moving said floating members and bell cranks whereby braking pressures and operation of said shoes may be selectively varied.

18. In a car retarding device, the combination of a brake shoe disposed adjacent a track rail, a floating member connected to said shoe and extending to a point on the opposite side of said rail, a member pivotally mounted on said floating member on said opposite side of the rail, said member having a portion engaged by a vehicle wheel moving on said rail to thereby move said member, said member having another portion forming a fulcrum whereby movement of

said first named portion by engagement by a vehicle wheel moves said floating member with respect to said fulcrum to cause said brake shoe to move to braking position.

19. In a car retarding device, the combination of a brake shoe disposed adjacent a track rail, a floating member connected to said shoe and extending to a point on the opposite side of said rail, a member pivotally mounted on said floating member on said opposite side of the rail, said member having a portion engaged by a vehicle wheel moving on said rail to thereby move said member, said member having another portion forming a fulcrum whereby movement of said first named portion by engagement by a vehicle wheel moves said floating member with respect to said fulcrum to cause said brake shoe to move to braking position, and means for returning said brake shoe to inoperative position when said vehicle wheel moves out of contact with said first named portion.

20. In a car retarding device, the combination of a brake shoe disposed adjacent a track rail, a floating member connected to said shoe and having an end adjacent said rail, a member pivotally mounted on said floating member on said end, said member having a portion engaged by a vehicle wheel moving on said rail to thereby move said member, said member having another portion forming a fulcrum whereby movement of said first named portion by engagement by a vehicle wheel moves said floating member with respect to said fulcrum to cause said brake shoe to move to braking position.

21. In a car retarding device, the combination of a brake shoe disposed adjacent a track rail, a floating member connected to said shoe and having an end adjacent said rail, a member pivotally mounted on said floating member on said end, said member having a portion engaged by a vehicle wheel moving on said rail to thereby move said member, said member having another portion forming a fulcrum whereby movement of said first named portion by engagement by a vehicle wheel moves said floating member with respect to said fulcrum to cause said brake shoe to move to braking position, and means for returning said brake shoe to inoperative position when said vehicle wheel moves out of contact with said first named portion.

ERNST FRÖLICH.
